LIGHTING FIXTURE DIFFUSER

Heinrich Gantenbrink, Menden, Kreis Iserlohn, Germany,
assignor to Prescolite Manufacturing Corporation,
Berkeley, Calif., a corporation of California

Filed Sept. 2, 1960, Ser. No. 61,999

Term of patent 14 years

(Cl. D48—16)

FIG. 1.

FIG. 2.

FIG. 3.

I claim:

The ornamental design for a lighting fixture diffuser, substantially as shown.
